AIR REGULATING APPARATUS

Edward G. Baer, Orrville, Ohio, and Robert R. Donaldson, Jr., Pittsburgh, Pa., assignors to Will-Burt Company, a corporation of Ohio

Application May 24, 1933, Serial No. 672,584

1 Claim. (Cl. 230—114)

This invention relates to automatic air regulating apparatus to be used for example with stokers, of the type to which fuel is fed intermittently, to control the rate of delivery of air to the fuel or fire bed of such stokers, as disclosed in our application Serial No. 552,645, filed July 2, 1931 of which this application is a continuation in part.

Domestic stokers, that is, stokers used with small home or apartment house furnaces, are necessarily of the intermittent feed type. While fuel is being fed to the furnace, air is supplied to the fuel bed under considerable pressure by a forced draft fan or blower; and during the intervals between the feeding periods, combustion is maintained by natural or chimney draft.

The length of time that the stoker is operated under forced feed and draft and the length of time that the fuel is burned under natural draft, depends largely upon the demand for heat as affected by the temperature of the outside air, among other things.

Because of the variations in the length of the operative and the inoperative periods of the stoker, and the variations in the requirements for heat, the thickness of the fuel bed will vary; consequently the resistance to the air flow through the fuel bed will vary. The thickness of the fuel bed will also vary unless proper steps are taken to insure the proper relation between the rate at which air is supplied to the fuel bed and the rate at which fuel is fed thereto.

Variations in the quality of the fuel being burned also affect the resistance of the fire bed to air flow.

In order to burn fuel efficiently in a stoker and thereby realize the economies to be had over hand fired methods, it is necessary that the forced air supply be closely regulated so that the air is delivered at substantially a constant rate regardless of the degree of thickness or thinness of the fuel bed. It is also essential that sufficient natural draft be supplied to maintain the fire alive during the inactive periods of the stoker.

An object of the invention is to provide apparatus that shall automatically respond to conditions affected by a change in the resistance to the flow of air, for example the resistance of a fuel bed and make automatic adjustments in the air supply to compensate for variations in the resistance to the flow of air through the fire bed.

Since the velocity of the air delivered by a fan or blower to the fuel bed of a stoker is, for all practical purposes, a function of the air flow

resistance of the fuel bed, it is proposed to so utilize the velocity of the air as a regulating medium, that a damper may be operated in such manner as to maintain a substantially constant supply of air to the fire bed. To accomplish such regulation, it is proposed to utilize a swinging target or vane, placed in the conduit, through which air is delivered by a fan or blower to the stoker, at a point between the damper and the air box or chamber of the stoker. It is proposed also to so proportion the target or vane that it shall offer substantially no resistance to the total flow of air to the fuel bed, so that the draft regulation may be accomplished solely by the damper.

Other objects of the invention will, in part, be apparent and will, in part, be obvious from the following description taken in conjunction with the accompanying drawing, in which:

Fig. 1 is a fragmentary view in perspective of a furnace provided with a stoker embodying one form of the invention;

Fig. 2 is a fragmentary view showing the fire pot and an air chamber of the stoker and a portion of the feed screw in operative relation to the furnace; and

Fig. 3 is an enlarged skeleton view in perspective showing the mechanism employed for controlling the supply of air to the fuel bed of the stoker.

Throughout the drawing and the specification, like references indicate like parts. The air regulating apparatus embodying the invention will be described in connection with its application to a stoker fired furnace.

With reference to Figs. 1 and 2 of the drawing, a furnace 1 is shown that is provided with a stoker 2 adapted to feed fuel to the furnace intermittently in accordance with the demand for heat. While fuel is being fed to the combustion chamber of the furnace, air for combustion is supplied by forced draft, natural draft maintaining the fire alive between heating periods.

Successful and economical operation of intermittently operated stokers depends largely upon the proper relation being maintained between the rate of fuel feed and the rate at which air is supplied to the fuel or fire bed. Since stokers of this type are designed to deliver fuel at a constant or uniform rate, it is essential to efficient operation that the air for combustion be supplied at a substantially constant rate. Best results are also obtained if the thickness of the fuel bed is maintained at predetermined value.

The thickness of the fuel bed is nearly always subject to change, unless the proper relation is

5 maintained between the rate of air supply and fuel feed. If the bed becomes too thick, there is a tendency to reduce the air flow therethrough; therefore the air, being insufficient, in passing through a thick fuel bed will come in contact with such a quantity of fuel in a state of combustion that the oxygen of the air will all be reduced to CO₂. But CO₂ in a highly heated state 10 coming in contact with incandescent carbon will be converted to CO. This results in the carrying away of a large amount of heat that would have been available for useful work had the reaction been stopped when all of the oxygen, or the larger part of it had been converted to CO₂.

15 If the fuel bed is too thin, the air flow through the fire bed tends to increase and become excessive. As a consequence, there is not sufficient contact between the air and the incandescent fuel to convert the larger part of the oxygen to 20 CO₂, and this excess oxygen passing through the fuel bed results in a loss of heat energy. Whenever an excess of air is used, a considerable amount of heat is carried away by such excess air, that would have been available for useful 25 work if the air had been properly regulated to suit actual requirements.

30 If the proper standard of combustion is once attained, and the proper relation is maintained between the rate of fuel feed, and air supply, it follows that the thickness of the fuel bed may be held at a substantially constant value. Such a condition is conducive to accurate regulation of the air supply, because the air flow resistance of the fuel bed remains fairly constant. This is apparent if it is taken into account that as the fuel bed becomes thinner, the resistance to air flow decreases; therefore the air supply increases which results in a further burning down and a further reduction in the thickness of the fuel bed. 40 Thus, a thin fuel bed when once developed, tends to become thinner and thinner until a point is reached where efficient combustion cannot be maintained.

45 On the other hand, if the fuel bed becomes too heavy, the increased air flow resistance thereof reduces the air flow through it and this in turn reduces the rate at which fuel will be burned. Since, however, fuel is preferably delivered at a constant rate, the fire tends to build up, further 50 increasing the fuel bed resistance, and again reducing the air flow until a very unsatisfactory operating condition is attained. Therefore, in view of the foregoing, it is quite essential to efficient operation, that the proper relation be 55 maintained between the rate of supply of air and the rate of fuel feed, in order that the thickness of the fire bed will be maintained at a substantially constant value, neither too thick nor too thin. The air regulating apparatus operates 60 to so regulate the air supply that the proper amount of air is delivered as the fuel bed thickness and its resistance varies.

65 The stoker includes a pot 3 having a burner ring 4 mounted thereon, and an air box or chamber 5. The top of the burner ring is formed with a vented flange 6 that bridges the space between the top of the air box and the burner ring. The bottom of the pot is formed with an inlet 9 to which a fuel feedpipe 10 is connected.

70 Fuel is fed through pipe 10 by a motor driven feed screw 14 to pot 3. Air for combustion is supplied to the fuel bed by a conduit 16 connected to a forced draft fan or blower 15. The air delivered to chamber 5 is delivered to the fuel 75 via burner ring ports 17, and ports 18.

Convenient, efficient and accurate regulation of the air supply may be obtained by means of a damper 21 and a device 22 that responds automatically to changes in velocity of the air delivered through conduit 16 to the fire bed and automatically adjusts the damper to maintain the air flow constant.

75 In practice, it is preferred to utilize a fan or blower that has a capacity to deliver air in excess of the amount that would be required with the 10 stoker operating at maximum capacity so that damper 21 will at all times be effective to regulate the air flow and maintain it at the rate required for efficient combustion. Thus, when the velocity responsive device 22 is once adjusted to 15 give the required air flow to a fuel bed of the desired thickness and air flow resistance, the damper will always occupy the proper position.

20 With such an arrangement, it follows that upon an increase in thickness of the fuel bed, resulting in an increase in the air flow resistance thereof, damper 21 will automatically be shifted to a position that reduces the air flow resistance through the damper by an amount equal to the increase in resistance of the fuel 25 bed. Likewise, if the fuel bed tends to become thin, the air flow resistance decreases and the velocity of the air tends to increase, whereupon the damper is automatically shifted towards closed position, until the decrease in fuel bed 30 resistance is made up by the damper and the velocity of the air restored to normal. In this manner, the damper is so adjusted that the total resistance to the flow of air through the damper and the fuel bed is maintained substantially constant. Under these conditions, efficient combustion can be obtained, because the proper relation between the supply of air and the rate of 35 fuel feed is maintained.

40 The velocity responsive device 22 comprises a vane or target 23 that is suspended by narrow straps 24 at its opposite ends from a shaft 25 extending through conduit 16 at the top thereof. The target is disposed near the bottom of the conduit and at such a distance from damper 21 45 that the turbulence of the air on the down stream side of the damper will not affect the true or actual velocity of the air impinging on the target.

45 The target is relatively small in area, so that it offers substantially no resistance to the total 50 flow of air through the conduit, but the area thereof is sufficient to offer the resistance required to swing it in response to and in accordance with variations in the velocity of the air.

55 One end of shaft 25 on which the target or vane is secured is provided with a crank arm 26 disposed on the outside of the conduit and this crank arm is connected by a link 27 to a crank arm 28 attached to the shaft on which damper 21 is mounted. The target shaft 25 is also provided 60 with an arm 29, that extends at substantially right angles to crank arm 26, on which a counterweight 30 is adjustably mounted. This counterweight may be moved towards or away from the target shaft so that the target and damper may 65 be counterpoised and urged towards such a position that the damper will be opened when the forced draft fan and the feed screw are not operating. This counterweight may also be utilized to adjust the damper to the proper position for 70 a given or desired rate of air flow to the fuel bed of the furnace.

75 In operation, assuming that the stoker is feeding fuel to the furnace at a predetermined rate, the counterweight 29 is adjusted to such a posi- 75

tion that the target will hold the damper in the proper position for efficient combustion. For this rate of fuel feed and air supply, the damper will occupy a certain definite position. But, if for some reason or other the air supply increases, the target will swing in the direction of the air flow and move the damper towards its closed position until the velocity of the air is restored to the proper value.

On the other hand, if the velocity of the air decreases, as the result of an increased thickness of the fuel bed or a change in the condition of the fuel bed which increases the resistance of the air flow through the same, the target will swing to a position such that the damper will be adjusted towards open position until the velocity of the air is restored to the proper value.

When the feed screw and the forced draft fan or blower stopped, counterweight 29 will swing the target to a position such as shown in Fig. 3, in which position the damper will be in substantially wide open position.

Since the regulation of the air supply by the damper is accomplished entirely in response to the velocity of the air supplied to the fuel bed, it follows that the total resistance to air flow offered by the damper and the fuel bed will be maintained at a substantially constant value. Therefore, for a given rate of fuel feed, the proper relation between the air supply and the fuel feed,

when once attained by manual adjustments, will be maintained automatically.

Having thus described our invention, what we claim as new and desire to secure by Letters Patent is:

Automatic air regulating apparatus comprising a conduit and a forced draft fan for delivering air under pressure through the conduit, a damper in the conduit, a freely movable target in and adjacent one wall of the conduit and disposed on the downstream side of the damper and having an air impinging surface of such small area compared to the transverse area of the conduit that it offers substantially no obstruction to air flow through the conduit, a rock shaft adjacent the opposite wall of the conduit, means for rigidly suspending said target from said rock shaft, a counterweight connected to said rock shaft and urging said target in a direction opposite to that in which it is urged by the velocity of the air flow, a crank arm on said rock shaft, and a link connecting said crank arm and damper whereby as the target moves to different positions in response to changes in velocity of the air, the damper is shifted to positions tending to maintain the rate of air flow substantially constant and to compensate for variations in the resistance offered to the flow of air from said conduit.
